(57) **CLAIM**

I claim the ornamental design for a cooking appliance, utensil and container, as shown and described within the figures.

DESCRIPTION

FIG. 1 is a first side view of a cooking appliance comprising a utensil according to a first embodiment of the invention.

FIG. 2 is a second side view of the cooking appliance comprising the utensil according to the second embodiment of the invention.

FIG. 3 is a third side view of the cooking appliance comprising the utensil according to the second embodiment of the invention.

FIG. 4 is a fourth side view of the cooking appliance comprising the utensil according to the second embodiment of the invention.

FIG. 5 is a bottom view of the cooking appliance comprising the utensil according to the second embodiment of the invention; and,

FIG. 6 is a perspective view of the cooking appliance comprising the utensil according to the second embodiment of the invention.
